HYDROCARBON CONVERSION

Jerry McAfee, Chicago, Ill., assignor to Universal Oil Products Company, Chicago, Ill., a corporation of Delaware

Application October 27, 1941, Serial No. 416,622

5 Claims. (Cl. 196—49)

This invention relates to a process for the production of motor fuel from residual hydrocarbon oils. More specifically, it is concerned with a process whereby a heavy charging oil such as topped crude or reduced crude may be converted to high yields of gasoline by a combination catalytic and thermal cracking operation.

In the catalytic cracking of hydrocarbons carbonaceous substances are deposited on the catalyst which tend to impair its activity and which therefore must be removed at frequent intervals to maintain the activity of the catalyst at a practical level. It has been observed that extremely high boiling hydrocarbons such as, for example, those present in reduced crudes tend to form carbonaceous catalyst deposits more rapidly than the lower boiling hydrocarbons and for this reason residual stocks have not ordinarily been employed directly as catalytic cracking charging stocks. However, various combinations of catalytic and thermal cracking have been proposed to process heavy oils, and in general these processes fractionate or flash the heavy charge to produce a vaporizable fraction which is cracked catalytically and a non-vaporizable fraction which is cracked thermally. Then by employing recycle operation, all of the charge may be converted to gas, gasoline, and residuum.

I have found that the overall gasoline yield which may be obtained from a given reduced or topped crude may be substantially increased over that obtained in processes of the above type by employing a particular sequence of steps on the charging oil.

To be more specific, this sequence may be briefly described as follows: The charging oil is subjected to a mild thermal cracking treatment such that the production of material boiling below the initial boiling point of the charge does not exceed 20%. The resultant products are then treated to separate a vaporous overhead from a non-vaporous residue. The vaporous overhead is subjected to catalytic cracking, the products therefrom fractionated to separate gasoline and gas from the reflux condensate, and the latter, together with the non-vaporous residue from the flashing operation, if desired, is subjected to a separate thermal cracking treatment to produce substantial yields of gasoline. Light and heavy fractions separated from the products of this second thermal cracking treatment are supplied to the catalytic and separate thermal cracking treatments, respectively.

In addition, several variations of this sequence

may be employed in some instances, and these variations will be discussed presently.

In one specific embodiment the present invention comprises subjecting a residual hydrocarbon oil to a mild thermal cracking operation, separating the resultant reaction products into a light fraction and a heavy fraction, subjecting said light fraction together with other hydrocarbon oils formed as hereinafter set forth to a catalytic cracking operation, recovering gasoline from the resultant products, subjecting the insufficiently converted hydrocarbons separated from the catalytic products together with the aforesaid heavy fraction to thermal cracking treatment, separating the reaction products into a gasoline fraction, an intermediate fraction, and a heavy fraction, supplying said intermediate fraction to said catalytic cracking treatment, and returning said heavy fraction to said thermal cracking treatment.

The accompanying diagrammatic drawing shows in side elevation one specific form of apparatus that may be employed to accomplish the object of this invention.

Referring now to the drawing, a residual hydrocarbon oil charge such as topped or reduced crude, containing high boiling hydrocarbons, is directed through line 1, valve 2, pump 3, line 4, and valve 5, whereafter it is commingled, if desired, with a diluting medium such as steam or gases formed in the process introduced through line 6 and valve 7. The composite material is then heated in coil 8 at a relatively low super-atmospheric pressure, usually less than 50 pounds per square inch gauge and in some cases at a sub-atmospheric pressure, to a temperature of from 700 to 1000° F. to effect a mild cracking, heat being supplied by means of furnace 9. The products from coil 8 are directed through line 10 containing valve 11 to separating chamber 12 wherein a separation is effected between the non-volatile residual hydrocarbons and the vaporized hydrocarbons. Chamber 12 is preferably operated at a slightly lower temperature and pressure than that maintained at the outlet of coil 8 and is ordinarily insulated to reduce heat losses therefrom, although no insulation appears in the drawing. It is intended that the cracking in coil 8 and chamber 12, as measured by the production of material boiling below the initial boiling point of the charge, will not exceed 20%.

The vapors from chamber 12 are withdrawn through line 13 and may be thereafter supplied without condensation through valve 14 and line 55 26 to heating coil 28 or may be directed through

line 15 and valve 16 and cooled and substantially condensed in condenser 17. The resulting condensate is then directed through line 18 and valve 19 to receiver 20 wherein a separation may be effected between the condensed hydrocarbons and whatever small amounts of non-condensable materials may be present. The non-condensable materials may be vented through line 21 and valve 22 while the condensate is directed through line 23, valve 24, pump 25, line 26, and valve 27. In most cases it may be preferable to supply the vapors from chamber 12 directly to coil 28 without condensation, since this procedure eliminates the necessity for the condensing and collecting equipment previously mentioned. It should also be noted at this point that instead of being merely a separating chamber in which a liquid condensate is separated from vapors, chamber 12 may also be, under some circumstances, a coking chamber, in which case it is desirable that several such chambers be employed in order that the operation may be continuous.

Continuing now with the flow, the vapor or condensate, as the case may be, in line 26 is commingled with a light fraction formed as herein-after set forth and supplied through line 10, and the resulting mixture is supplied to heating coil 28 as previously noted, wherein it is heated to a temperature of from 800 to 1100° F., preferably of from 900 to 1000° F. at a pressure ordinarily in the range of from atmospheric to 100 pounds per square inch, heat being supplied by means of furnace 29. It is necessary, of course, that if the vapors are supplied directly from chamber 12 through line 13 and valve 14 that the pressure in coil 28 be less than that employed in chamber 12. The substantially vaporized hydrocarbons from coil 28 are then directed through line 30 and valve 31 to catalytic reaction chamber 32 wherein they are contacted with a cracking catalyst.

In the case here illustrated, reactor 32 preferably comprises a cylindrical vessel containing one or more beds of catalytic material, said vessel being sufficiently insulated to reduce radiation losses therefrom, so that the reaction may be accomplished substantially adiabatically. If desired, however, the reactor may be of the heat exchanger type wherein the catalyst is maintained in indirect heat exchange relationship with a heat exchange fluid adapted to supply heat to or remove heat from the catalytic mass.

Among the catalysts which have been found to be effective in the cracking of hydrocarbons are silica or other siliceous and refractory materials composited with compounds selected from the group consisting of alumina and zirconia. Natural catalysts of this type comprise, for example, hydrosilicates of alumina, either untreated or treated. These catalysts may be synthetically prepared by precipitating hydrated alumina and/or hydrated zirconia from suitable compounds thereof on a hydrated silica base followed by washing, pelleting, and calcining at temperatures of from 800 to 1500° F. Although the catalysts above recited are generally considered to be the preferred ones, their use is not to be construed as a limiting feature, for other catalysts well known to those in the art may be employed.

As previously stated, the carbonaceous deposit formed in the catalyst during the cracking reaction is removed at frequent intervals so that it is desirable to employ two reactors and in some cases more than two, so that at least one reactor may be processing at any one time, thereby per-

mitting the processing to be continuous. Regeneration of the used catalytic material may be accomplished in several ways, perhaps the most convenient of which is the method of passing oxygen-containing regenerating gases in contact with the used catalyst, thereby burning the carbonaceous deposit from the surface of the catalyst.

Although the drawing and accompanying description have been directed specifically toward catalytic operations of the type in which a hydrocarbon vapor is passed through a fixed bed of catalytic material, it is entirely within the scope of this invention to employ any other well known type of operation. For example, the catalytic cracking step may be of the type in which a powdered catalyst is injected into a stream of hydrocarbon vapors and the resulting mixture supplied to a reactor in which the mixture has an upward velocity component. In this way, a greater concentration of catalyst may be maintained in the reactor than is present in the entering stream, since the net upward velocity of the hydrocarbon vapors is greater than that of the powdered catalyst. The catalyst may then be separated from the reaction products by any suitable means.

It is also within the scope of this invention to employ a powdered catalyst cracking operation in which the catalyst is suspended in the oil and the resulting slurry supplied to a cracking coil and, if desired, to a reaction chamber. In this particular variation, any suitable means such as cyclone separators and the like may be utilized for the separation of reactant vapors from the spent powdered catalyst. In both of these powdered cracking operations the catalyst may be regenerated and recirculated, thereby providing for a continuous process.

Returning again to the drawing, reaction products from reactor 32 are withdrawn through line 33 containing valve 34 and are thereafter supplied to fractionator 35 wherein a separation is effected between an overhead product of the desired end point and a bottoms fraction comprising insufficiently converted hydrocarbons. The overhead product consisting of gasoline and gas is withdrawn through line 36 containing valve 37 and may thereafter be cooled to condense the gasoline present therein, and the resulting two-phase mixture separated in a suitable receiver. A portion of the condensed gasoline may be returned to the top of fractionator 35 to serve as a reflux. The remaining portion together with the gases is recovered as a product of the process.

Turning now to the thermal cracking section of the combination process, the combined feed to this section ordinarily comprises the bottoms from column 35 supplied through line 38', valve 37', pump 38, line 39, and valve 40; the bottoms from fractionator 41 supplied through line 42, valve 43, pump 44, line 45, and valve 46; and the bottoms from chamber 12 supplied through line 47, valve 48, pump 49, line 50, and valve 51. In the event that chamber 12 is employed to produce coke rather than liquid bottoms, the last named fraction will not, of course, be employed as part of the thermal combined feed but will be removed as solid coke. In any event, the combined feed is supplied through line 52 to heating coil 53 wherein it is raised to a cracking temperature ordinarily in the range of from 800 to 1100° F. and at a superatmospheric pressure usually less than 500 pounds per square inch to effect substantial conversion thereof to lighter hydrocarbons,

heat being supplied by means of furnace 54. The reaction products from coil 53 are passed through line 55 containing valve 56 into reaction chamber 57 where further cracking is effected at a slightly lower temperature and pressure. Chamber 57 is ordinarily insulated to prevent excessive loss of heat by radiation therefrom, although no insulation appears in the drawing.

The products from chamber 57 are directed through line 58 containing valve 59 into vaporizing and separating chamber 60, ordinarily operated at a pressure of from 30 to 150 pounds per square inch and at a temperature of from 700 to 850° F. to effect a separation between liquid residue and vaporous conversion products. The liquid residue is withdrawn through line 61 containing valve 62 and may thereafter, if desired, be cooled and returned to the top of chamber 60 or to line 52 to serve as a quenching medium. The vapors from chamber 60 are withdrawn through line 63 containing valve 64 and are thereafter directed to fractionator 41 wherein the vapors are fractionated into a distillate fraction of the desired end point, an intermediate boiling range fraction ordinarily having an end point not in excess of 650° F., and a heavy fraction. The distillate fraction comprising gasoline and gas is withdrawn through line 65 containing valve 66 and may thereafter be cooled, etc. in a manner similar to that employed on the overhead from fractionator 35. The intermediate fraction from fractionator 41 is directed through line 67, valve 68, pump 69, line 70, and valve 71 to line 26 wherein it forms a part of the feed to the catalytic section as hereinbefore set forth. The heavy fraction separated in chamber 41 is returned to the thermal section by way of line 42, etc., as previously noted.

The following example is given to demonstrate the advantages of this invention, although the invention is not intended to be limited thereby.

In a semi-commercial size plant a series of tests were made in which a residual charging oil was heated, flashed to separate a vaporous fraction from a non-vaporous fraction, and the vaporous fraction condensed, reheated, and supplied to the catalytic cracking chamber. The bottoms obtained from fractionation of the products of catalytic cracking were combined with the non-vaporous fraction from the flashing operation and thermally cracked. The heavy residue was separated from the products of thermal cracking and the remaining products boiling above gasoline were separated into a light and heavy fraction. The heavy fraction was returned to the thermal cracking step while the light fraction was supplied to the catalytic cracking operation. Gasoline was recovered from both of the cracking steps.

These tests were made at slightly different temperatures and times of reaction in the flashing step and resulted therefore in varying degrees of thermal cracking in the flashing operation. In each test, however, approximately the same percentage of the charge was taken overhead from the flashing operation so that the effect of varying degrees of thermal cracking in a flashing operation could be determined. The charging oil for each of the tests was a Mid-Continent reduced crude having an A. P. I. gravity of 25.4° and an initial boiling point of 555° F.

A summary of the data so obtained as well as the conditions of operation of the tests is presented below:

5		Test number		
		1	2	3
10	Percentage of charge taken overhead from flashing operation and supplied to the catalytic cracking operation	86	82	84
15	Approximate percentage of products of flashing operation boiling below the initial boiling point of the charging oil (555° F.)	14	6.8	1
15	Gasoline yield volume percent of charge:			
	Catalytic	42.8	40.6	38.8
	Thermal	23.0	21.7	19.2
	Total	65.8	62.3	58.0
20	Gasoline motor method octane numbers:			
	Catalytic	79.6	79.6	79.8
	Thermal	70.1	69.9	69.8
	Total	78.2	76.1	76.2
25	Operating conditions flashing section:			
	Heater outlet temperature, °F.	847	827	812
	Flash chamber top temperature, °F.	825	819	805
	Flash chamber pressure, pounds absolute	8	7	5
30	Catalytic section:			
	Length of process period, minutes	90	90	90
	Space velocity	2.05	2.05	2.03
	Reactor inlet temperature, °F.	966	959	963
	Reactor outlet temperature, °F.	916	917	918
35	Thermal section:			
	Heater outlet temperature, °F.	931	925	927
	Reaction chamber pressure, pounds gauge	200	200	200

The above tests show the beneficial effect of mild thermal cracking in the flashing operation inasmuch as a higher gasoline yield may be obtained thereby.

I claim as my invention:

1. A process for the conversion of hydrocarbon oil which comprises subjecting said oil to a relatively mild thermal cracking, separating the resultant conversion products into vapors and residue, subjecting said vapors, including all of those boiling below the initial boiling point of said oil, to catalytic cracking, fractionating resultant vaporous conversion products independently of said vapors to condense and separate fractions higher boiling than gasoline, subjecting resultant reflux condensate to thermal cracking independently of said oil, independently fractionating resultant thermally cracked vaporous conversion products to condense and separate a light reflux condensate and a heavier reflux condensate, supplying the latter to the last mentioned thermal cracking step and supplying light reflux condensate to the catalytic cracking step.
2. The process of claim 1 further characterized in that said oil is subjected to cracking under conditions such that substantially no more than 20% is converted to material boiling below the initial boiling point of the oil.
3. The process of claim 1 further characterized in that a vaporous diluent is added to said oil prior to cracking.
4. The process of claim 1 further characterized in that a vaporous diluent comprising hydrocarbon gases is combined with said oil prior to cracking.
5. The process of claim 1 further characterized in that said residue is subjected to thermal cracking in the last mentioned thermal cracking step.

JERRY McAFFEE.
